(57) **CLAIM**

The ornamental design for a device for inducing microfluidic flow, as shown and described.

DESCRIPTION

1. Device for inducing microfluidic flow

Fig. 1.1 is a perspective view of a device for inducing microfluidic flow, showing our new design;

Fig. 1.2 is a top plan view thereof;

Fig. 1.3 is a bottom plan view thereof;

Fig. 1.4 is a front elevation view thereof;

Fig. 1.5 is a rear side elevation view thereof;

Fig. 1.6 is a left side elevation view thereof; and

Fig. 1.7 is a right side elevation view thereof.

In the reproductions, the gray color wash depicts portions of the device for inducing microfluidic flow that form no part of the claim.
